UNITED STATES PATENT OFFICE.

LEON LEWANDOWSKI, OF DEPEW, NEW YORK

WIRE-CUTTER.

1,283,824.

Specification of Letters Patent.

Patented Nov. 5, 1918.

Application filed April 5, 1918. Serial No. 226,873.

To all whom it may concern:

Be it known that I, LEON LEWANDOWSKI, a citizen of Russia, residing at Depew, in the county of Erie and State of New York, have 5 invented certain new and useful Improvements in Wire-Cutters, of which the following is a specification.

The primary object of the invention is the provision of a wire cutting bayonet for 10 a rifle adapted for ready operation by the soldier carrying the fire-arm, means being provided for retaining the device inoperative when not in use.

A further object of the device is the provision of a bayonet adapted for detachable connection with a rifle barrel and provided with a shiftable cutting member normally disposed in its closed inoperative position with the shape of the blade substantially un- 20 broken and ready for immediate use when desired.

A still further object is to provide a foldable wire-cutting attachment for removable rifle bayonets, the attachment being so arranged as not to interfere with the ordinary uses of the bayonet, although the device may be quickly altered into form for cutting wire barriers and similar formations whenever the occasion requires.

30 In the drawings forming a part of this application and in which like numerals refer to corresponding parts throughout the several views:

Figure 1 is a side elevation of a portion of 35 a rifle barrel having my device operatively mounted thereon, portions of the device being shown by dotted lines in their open arrangement;

Fig. 2 is an inverted plan view of the 40 same;

Fig. 3 is a side elevational view of the device detached and in its folded arrangement;

Fig. 4 is an enlarged plan view of the 45 hinged portions of the wire cutter;

Fig. 5 is an elevational view thereof in its open extended arrangement;

Fig. 6 is a transverse sectional view taken upon line 6—6 of Fig. 1; and

50 Fig. 7 is a perspective view of the hinged link employed with the device.

My invention broadly consists of a bayonet 10 of substantially the usual form adapted for detachably mounting upon a 55 rifle barrel 11 to project forwardly of the

muzzle 12 of the barrel, a hinged cutting member 13 of the bayonet being designed for severing wires and similar objects.

The bayonet 10 has a shank 14 provided with a transverse guard 15 having an eye 16 at one end for slidably positioning the bayonet upon the barrel 11. The free end of the shank 14 is formed with a longitudinal side socket 17 for receiving a lug 18 projecting from the bottom of the barrel 11 60 while a spring latch 19 passes transversely through the socket 17 and the shank 14 and seats within a corresponding transverse groove in the outer free end of the lug 18 for detachably securing the shank 14 upon 65 the barrel 11.

The cutting member 13 is in the form of a blade pivoted to the side of the bayonet 11 by a rivet 20 having a protecting loop 21 overlying the member 13. The said cutting 70 member has a sharpened inner edge 22 adapted for coöperating with a complementally formed curved cutting edge portion 23 of the bayonet 10, whereby wires positioned between the cutting portion 13 and the main 75 portion of the bayonet 10 after the member 13 is swung outwardly as shown by dotted lines in Fig. 1, may be readily severed by closing the edges 22 and 23 together.

The cutting member or blade 13 is guidingly positioned between the bifurcated portions 24 of the guard 15 at the opposite end thereof from the eye 16 while a hinged link 25 is pivoted as at 26 to the inner end of the blade 13 and is also pivoted as at 27 to 80 a downwardly extending post 28 carried by the shank 14. A handle 29 is foldably connected to the rear end of the link 25 by a hinged block 30 pivotally connecting the adjacent ends of the link 25 and handle 29, 85 whereby the said handle may be moved laterally and positioned alongside of the bayonet 10 whenever desired, as indicated in Fig. 3 of the drawings, at such times, for instance, as when the bayonet 10 is removed 90 from the barrel 11. A bracing hook 31 projects from the hinged end of the handle 29 for lateral wedging reception within a transverse slot 32 in the adjacent edge of the link 25, and, whereby the handle 29 will be 95 retained in its outstretched operative position projecting from the link 25 for employment in shifting the blade 13. It will be evident that the handle 29 may be forcibly shifted however upon its hinged block 100 110

30 for removing the hook 31 from the wedging slot 32 when it is desired to fold up the device.

A boss 33 is provided upon the bottom 5 of the barrel 11 with a finger 34 adapted to be received into a groove 35 formed at the free end of the handle 29, while a sliding latch 36 upon the handle is adapted to underlie the finger 34 for securing the handle 10 to the boss 33 and locking the wire cutting means in its inoperative position.

With the cutter positioned as shown in Figs. 1 and 2 of the drawings, the latch 36 may be readily released for permitting 15 the handle 29 to be swung outwardly to open the blade 13 as shown by dotted lines in Fig. 1. A wire or other object being positioned between the blade 13 and the opposite cutting edge 23 of the bayonet 10, a 20 movement of the handle 29 toward the barrel 11 will forcibly close the blade 13 upon the wire for severing the same. The hinged connection 26 between the link 25 and the blade 13 provides a strong leverage for the 25 cutting operation after the manner of a toggle joint so that great force can be brought to bear upon the wire positioned between the cutting edges 22 and 23. A finger or holding loop 37 is provided upon the outer 30 side of the handle 29 adjacent its free end. It will be evident that when the blade 13 is in its closed position with the handle 29 locked to the boss 33 the device interferes in no way with the use of the bayonet 10, 35 the opposite edges thereof being substantially unimpaired throughout their entire length.

What I claim as new is:—

1. A device of the class described comprising a bayonet having a cutaway side portion, a blade pivoted to the bayonet adapted for fitting said cutaway portion when in its closed position, means adapted for detachably connecting the bayonet to a 40 rifle barrel, a toggle-operating link hingedly connected to the bayonet and to the inner end of the blade, and a handle pivoted to the free end of said link adapted for folding arrangement adjacent the side of the bayonet when the device is not in use.

2. In combination, a bayonet having a cutaway side portion provided with a cutting edge, a blade adapted for coöperating

with the said edge for positioning within the cutaway portion when in its closed position, pivotal connections between the said blade and bayonet, a post upon the bayonet rearwardly of said pivotal connections, a toggle-operating link pivoted to the free end of said post and hingedly connected to the adjacent end of the blade, and an operating handle for said link.

3. In combination, a bayonet having a cutaway side portion provided with a cutting edge, a blade adapted for coöperating with the said edge for positioning within the cutaway portion when in its closed position, pivotal connections between the said blade and bayonet, a post upon the bayonet rearwardly of said pivotal connections, a toggle-operating link pivoted to the free end of said post and hingedly connected to the adjacent end of the blade, the said link having a wedge-shaped slot therein, a handle hinged for lateral movement to the free end of said link, a bracing hook upon said handle adapted for frictional engagement within the said slot when the handle is in its inoperative extended position, and a finger loop adjacent the free end of the handle.

4. In combination, a bayonet having a cutaway side portion provided with a cutting edge, a blade adapted for coöperating with the said edge for positioning within the cutaway portion when in its closed position, pivotal connections between the said blade and bayonet, a post upon the bayonet rearwardly of said pivotal connections, a toggle-operating link pivoted to the free end of said post and hingedly connected to the adjacent end of the blade, the said link having a wedge-shaped slot therein, a handle hinged for lateral movement to the free end of said link, a bracing hook upon said handle adapted for frictional engagement within the said slot when the handle is in its operative extended position, a finger loop adjacent the free end of the handle, a guard transversely carried by the bayonet having a guiding portion at one end for the blade and a barrel-receiving eye at its opposite end, and attaching means at the rear ends of the bayonet and handle.

In testimony whereof I affix my signature.

LEON LEWANDOWSKI.
